UNITED STATES PATENT OFFICE.

PATRICK W. KIERNAN, OF LOWELL, MASSACHUSETTS, ASSIGNOR TO LOWELL BLEACHERY, OF LOWELL, MASSACHUSETTS, A CORPORATION OF MASSACHUSETTS.

KIER.

Application filed May 18, 1923. Serial No 639,984.

To all whom it may concern:

Be it known that I, PATRICK W. KIERNAN, a citizen of the United States, residing at Lowell, in the county of Middlesex and State of Massachusetts, have invented certain new and useful Improvements in Kiers; and I do hereby declare the following to be a full, clear, and exact description of the invention, such as will enable others skilled in the art to which it appertains to make and use the same.

The present invention relates to an improvement in kiers. The object of the invention is to produce an automatic vomiting kier operating to maintain a uniform pressure in the kier during the boiling process. To this end the present invention consists in the kier hereinafter described and particularly defined in the accompanying drawing illustrating the kier in sectional elevation.

The following is a description of the apparatus with reference to the accompanying drawings. The kier A of usual form and construction is provided with the usual removable cover C and vent X. The steam pipe N leads to the injector I at the bottom of the kier. A blow off pipe U leads from the bottom of the kier. The vomiting pipe M leads from the injector I to the top of the kier where it enters the top and leads to the spray head R where the liquor S is sprayed upon the goods D in the kier. These goods rest on the stones Q lying on the grating in the bottom of the kier. The vomiting pipe is provided near the top with the safety valve W. The steam pipe is provided with a balanced valve T which is opened and closed by a diaphragm regulator F, the lever of the steam valve being connected by means of the chain H running over the pulleys O to the piston L of the regulator. A small regulator pipe G connects the vomit pipe with the regulator. The mode of operation is as follows:—The goods are placed in the kier, the spray head swung into position, the cover is put on and secured hermetically, and then a certain amount of liquor is introduced through the blow off pipe U which flows into the bottom of the kier and at the same time flows up through the vomit pipe and into the kier at the top, the vent being open at this time. Then the steam is turned on to the pipe N and the valve T being open, it flows down to the bottom of the kier and

lifts the liquor by means of the injector to the top of the kier and sprays it on to the goods. The steam continues to flow until the pressure at the regulator is such as to cause it to operate to shut off the steam by closing the valve T. During this part of the operation the vent is closed and the kier is brought up to pressure. Radiation of heat from the kier causes the pressure to fall and when it falls below the critical point, the regulator opens the steam valve T again and forces liquor from the bottom of the kier to the top and sprays it upon the goods. When the liquor is exhausted in the bottom of the kier, steam rises in the vomit pipe and when it reaches the top of the pipe it causes a pronounced rise in pressure which operates the regulator to close the valve T so as to prevent any dry steam from being blown into the top of the kier which would destroy the goods on top. The operation of the kier is automatic, steam being admitted intermittently whenever the pressure in the kier falls below the predetermined amount determined by the regulator. The regulator, it will be observed, may be adjusted to various pressures by adding to or taking from the weights applied to the regulator lever. In operation the intermittent admission of steam to the injector is at such short intervals that the resulting pressure in the kier remains practically uniform at all times. During the boiling process there is some rise of the liquor level due to the condensation of the steam used, as is usual in this class of kiers.

By means of this automatic regulation of the admission of steam to the kier for lifting liquor from the bottom and vomiting it upon the goods at the top, the variations due to hand control of steam admission are eliminated and the danger of blowing dry steam on to the top of the goods is avoided, with the result that a kier of improved operation is secured.

Having described the invention, what is claimed is:—

1. A vomiting kier having an injector connected with the bottom of the kier, a steam pipe leading to the injector provided with a steam valve, a vomit pipe connecting the injector with the top of the kier, and an automatic regulator controlled by the pressure in the vomit pipe, operating on a rise of pressure in the vomit pipe to close the

110

steam valve and on a fall in pressure in the vomit pipe to open the steam valve.

2. A vomiting kier having, in combination, a kier, a steam pipe for supplying steam to the kier, an injector connected with the steam pipe, a vomiting pipe connecting the injector with the top of the kier, and

automatic means acting upon a rise in pressure at the top of the kier to shut off the steam supply and upon a drop in pressure at the top of the kier to open the steam supply. ¹⁰

PATRICK W. KIERNAN.
